COMBINATION EXHIBITION HALL AND PLANETARIUM

Lawrence S. Litchfield, New York, N.Y., assignor to
Theodore J. Kauffeld, New York, N.Y.

Filed Feb. 1, 1961, Ser. No. 63,792

Term of patent 14 years

(Cl. D13—1)

FIGURE 1 is a front elevational view of a combination exhibition hall and planetarium, showing my new design; FIGURE 2 is a top plan view;

FIGURE 3 is a view similar to FIGURE 1 with the front and rear supporting columns omitted and the front of the ring-shaped section broken away to reveal the central spherical section, the cross-sectioning being substantially along the line 3—3 of FIGURE 2;

FIGURE 4 is a fragmentary cross-sectional view substantially along the line 4—4 of FIGURE 1; and

FIGURE 5 is an enlarged cross-sectional view substantially along the line 5—5 of FIGURE 1.

The article is symmetrical and has six symmetrical supports and windows, and the rear is substantially the same as the front shown in FIGURE 1.

I claim:

The ornamental design for a combination exhibition hall and planetarium, substantially as shown and described.
